(74) Attorney, Agent, or Firm — Gerard J. McGowan, Jr.

(57) **CLAIM**

The appearance of a bottle, as shown and described.

DESCRIPTION

FIG. 1 is a front perspective view from the top right side;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines in the drawings showing of the bottle illustrate the portions of the bottle that form no part of the claimed design.

1 Claim, 6 Drawing Sheets(56)
